UNITED STATES PATENT OFFICE.

WILLIAM A. LYNCH, OF LOS ANGELES, CALIFORNIA.

GAS-FURNACE.

971,859.

Specification of Letters Patent.

Patented Oct. 4, 1910.

Application filed April 8, 1909. Serial No. 488,786.

To all whom it may concern:

Be it known that I, WILLIAM A. LYNCH, citizen of the United States, residing in the city of Los Angeles, county of Los Angeles, 5 and State of California, have invented new and useful Improvements in Gas-Furnaces, of which the following is a specification.

The object of my invention is to provide a gas furnace with large heating capacity 10 and to carry off the fumes or carbon mon-oxid and prevent the same from commingling with the air that is used for heating purposes, and at the same time to utilize the heat usually escaping with such fumes. 15 I accomplish this object by the furnace de-scribed herein and illustrated in the accompanying drawings in which:—

Figure 1 is a side elevation partly in section and partly broken away, of my im-20 proved furnace. Fig. 2 is a section on the line 2—2 of Fig. 1.

In the drawings 5 is the external casing which is preferably of sheet metal and pref-25 erably quadrangular. Opening from the top of this casing are the usual service pipes 6 which carry the heated air to the place of use. There may be as many of these service pipes as are desired, the number depending upon the capacity of the furnace. At the 30 bottom of the casing on the sides thereof are the air inlet openings 7 through which the air to be heated passes. At one side above the air inlet the outer casing is provided with a door 8 to provide additional facility 35 for inspecting the interior of the casing. There may be a door on the other side. The casing is also provided with a lining 9 which is connected to and held separated from the casing by brackets 10 thereby providing an 40 air flue 11 between the exterior casing and the lining.

Projecting through one end of the casing are the gas burners 12, of which there may be any desired number, I have shown four 45 as I consider that number desirable for an ordinary sized furnace, and they are of any approved construction, and are provided with the usual pilot lights, not shown. These burners run longitudinally and close 50 to the back plates 13 of what may be termed the burner chamber. These plates are secured to the end walls 14 and 15. On the front of these back plates are sheets of asbestos 16 which hold the flame in the usual manner of gas furnaces. Below the burners 55 these back plates curve outwardly and form

supports for the polished reflectors 17 which deflect the rays of heat when the burner is in operation.

18 are the side walls and 19 the bottom of 60 the burner chamber.

The end walls 14 and 15 of the burner chamber are extended upwardly and form the end walls of what may be denominated the fume chamber 20. The lower portion or 65 throat 21 of the fume chamber is of the same size as the lower portion of the burner chamber, as best shown in Fig. 2. Above the throat the fume chamber widens and in the widened portion is provided with a plurality 70 of air tubes 22 through which a portion of the air passes on its way to the service pipes. Within the fume chamber is a V-shaped de-75 flector 23 which deflects the fumes that pass into the chamber around the outer air tubes 22. In one end of the fume chamber is an outlet port 24 which opens into an outlet pipe 25 to which the vent pipe, not shown, may be connected to carry the fumes outside 80 the building, or to a chimney.

By this construction the air to be heated passes directly in front of the burners and is subjected to the direct waves of heat produced thereby. The fumes, or carbon mon-oxid and a portion of the heated air passes 85 upwardly through the opening between the back plate and the bottom of the throat of the fume chamber, and is deflected upwardly around the air tubes and then passes downwardly and out of the fume chamber. 90 In their passage through the fume chamber these gases heat the exterior walls thereof as well as the walls of the air tubes which pass therethrough, thus giving additional radiat-ing surface and efficiency to the furnace. 95 It will be observed that the air is broken up into a large number of ascending currents, and it is thereby subjected to the action of a large radiating surface whereby it becomes highly heated. The outer casing is pref-100 erably quadrangular and the burners are preferably so arranged that the greater por-tion of the air to be heated for use passes through vertical flues.

Having described my invention what I 105 claim is:—

1. An improved gas heater comprising an outer casing of sheet metal having a pipe connected to the top to carry off the heated air, and having air inlets at the bottom in 110 the sides thereof; a burner projecting into said casing and across the lower portion

thereof; a back plate behind said burner inclined to project above and in front of the vertical plane of the burner; a fume chamber extending upwardly above said back 5 plate having the top portion above the back plate projecting beyond the vertical plane of the back plate with an opening into the fume chamber above the back plate and an outlet passage at one end; and a plurality of 10 air heating tubes extending vertically through the projecting portions of said fume chamber.

2. An improved gas heater comprising an outer casing of sheet metal having a pipe or 15 pipes connected to the top thereof to carry off the heated air; a lining separated from the casing to form an air flue therebetween, said lining extending around the side and end walls of the casing, except at the top and 20 the bottom; a plurality of gas burners projecting into said casing across the lower portion thereof; back plates behind said burners inclined to project above and in front of the vertical plane of the burners; a fume 25 chamber extending upwardly having an outlet passage at one end near the center thereof, said fume chamber being situate above said back plates and overhanging them and having an opening in the bottom thereof 30 above the back plates to receive the products of combustion; and a plurality of air heating tubes extending through the projecting portions of said fume chamber.

3. An improved gas heater comprising an outer quadrangular casing of sheet metal having pipes connected to the top thereof to carry off the heated air; a lining extending 35 around the side and end walls of the casing except at the top and bottom and separated 40 from the casing to form an air flue therebetween; a plurality of gas burners projecting into said casing across the lower portion

thereof; back plates behind said burners inclined to project above and in front of the vertical plane of the burners; asbestos on 45 said back plates at and above said burners; a fume chamber extending upwardly above said back plates having an outlet passage at one end near the top thereof and having an inlet at the bottom thereof, said inlet being 50 wider than the distance between the top edges of said back plates; a plurality of vertical air heating tubes extending through the outer portions of said fume chamber; and a deflector in said fume chamber. 55

4. An outer casing having air inlets at the bottom thereof, and air outlets at the top thereof; gas burners within the outer casing above the plane of the air inlets; deflecting plates back of the burners, said plates projecting at the top thereof beyond the vertical plane of the burners and terminating above the burners; a fume chamber above and projecting beyond the back plates and having an opening in the bottom thereof a 60 little larger than the opening between the top edges of the back plates and having an outlet port above said bottom opening; vertical flues extending through the portion of the fume chamber which projects beyond the 65 back plates; and a deflector in said fume chamber separating the bottom opening from the outlet port, said deflector extending upwardly and outwardly and terminating at the outer vertical tubes a distance 70 from the top of the chamber. 75

In witness that I claim the foregoing I have hereunto subscribed my name this 5th day of March 1909.

WILLIAM A. LYNCH.
